OVERALL

Filed April 18, 1925

UNITED STATES PATENT OFFICE

ERICK O. FELLROTH, OF MINNEAPOLIS, MINNESOTA, ASSIGNOR TO MARTIN BROTHERS COMPANY, OF MINNEAPOLIS, MINNESOTA, A CORPORATION OF MINNESOTA

OVERALL

Application filed April 18, 1925. Serial No. 24,081.

My invention relates to improvements in overalls.

An object of the invention is to provide an improved garment of the present nature, the same having a drop-seat and belt-members associated therewith, said belt members serving not only to releasably hold said drop-seat closed, but also to draw and hold the waist of the garment snugly and smoothly about the body of the wearer.

Another object of the invention is to supply a garment, as above, the drop-seat portion being tapered upwardly to limit the width of said portion at the waist of the garment and thereby permit of the extension of the back of the body portion at the waist line, whereby the ends of the suspender straps, at the back of the garment, may be attached to said body portion.

With the foregoing and other objects in view, which will appear in the following description, the invention resides in the novel combination and arrangement of parts and in the details of construction hereinafter described and claimed.

In the drawings, Figs. 1 and 2 are front and rear views respectively, of a garment embodying my invention; Fig. 3 is a transverse, detail sectional view of the same, said view being taken as on the line 3—3 of Fig. 2 and Fig. 4 is an elevational view in detail illustrating the manner in which the drop-seat of the garment is released upon the unfastening of the belt members.

Referring to the drawings, it will be noted that the illustrated embodiment of the present invention is generally similar in outward appearance to the conventional types of overalls, the same including the usual hip encircling body portion A, legs 10 and fly 11. The instant garment further includes front pockets 12, an apron 13 and crossed suspenders or shoulder-straps 14 attached to the upper margin of the apron 13 and to the back of the body A of the garment at the waist line thereof. Differing from ordinary overalls, the instant garment has a drop-seat portion a, which opens downward from the waist line of the body portion A. This drop-seat a, at the lower part thereof, occupies substantially the

entire width of the body portion A, said drop-seat a being tapered rather sharply upward with the result that the width of the drop-seat a at the free edge thereof is less than the distance between the ends of the shoulder straps or suspenders 14 at the back of the garment. And it will be noted in this connection that the body portion A is formed with rear extensions 15^a which normally underlap the sides of the drop-seat a and, further, that it is to these extensions 15^a that the suspenders 14 are fastened to the back of the garment. Two belt-straps 16 are furnished, one belt-strap 16 being attached to one body-portion extension 15^a at the junction of one shoulder-strap 14 with said extension, the other belt-strap 16 being attached to the opposite body-portion extension 15^a at the junction of the other shoulder-strap 14 therewith. Opposed loops 17, one for each belt-strap 16, are fastened to the drop-seat a, one loop at each free corner of said drop-seat. The free end of each belt-strap 16 is threaded through its respective adjacent loop 17. A buckle 18 of conventional pattern fitted to one belt-strap 16 provides an adjustable bight 19 therein in which is caught a fastener member 20 in the form of an eye. The free end of the other belt-strap 16 is equipped with a companion fastener member 21 comprising the usual type of hook for complementing an eye.

In use, the belt-straps 16 are unfastened, one from the other, when the garment is put on. After the shoulder-straps 14 have been adjusted, each belt-strap 16 is turned forward over the near hip, the ends of said belt-straps being caught together in front of the garment by engaging the hook 21 with the eye 20. In bringing together the ends of the belt-straps 16, the drop-seat portion a of the garment is closed by the action of the belt-straps 16 sliding in the loops 17 and said drop-seat portion is thus held until said belt-straps 16 are again loosened and slackened to permit of the lowering of said drop-seat. In pulling upon the belt-straps 16 to engage the hook 21 in the eye 20, the garment, at the waist line thereof, is snugly and smoothly drawn against the body of the wearer. This

effect is produced by the belt-straps 16, which pull forwardly upon the drop-seat from the upper corners thereof and which pull rearwardly upon the body-portion A of the garment from the points where said belt-straps are attached thereto. With the bights 16^a (Fig. 3) in the belt-straps 16 sliding in the loops 17, during the fastening of said belt-straps, the sides of the drop-seat are smoothly lapped over the extensions 15^a of the body portion A, all pleats, or wrinkles being drawn out of the garment at the waist line, where said garment is belted to the wearer's body. The loops 17 on the drop-seat *a* are arranged so that the bights 16^a in the belt-straps 16 will bring said loops closely adjacent to the attached ends of said belt straps 16 and to the junctions between the suspenders 14 and the body portion A. This feature prevents any objectionable sagging of the drop-seat *a* that might otherwise occur, were the belt-straps 16 to be left very loose about the wearer's body. Properly tightened, said belt-straps 16 cause the main weight of the garment, including the weight of tools or other objects in the pockets thereof, to be carried at the hips, thus freeing the wearer from such burden upon his shoulders and permitting of unhampered movements in the bending of his body and in the movement of his arms. Since the shoulder-straps 14 are relieved from carrying the main weight of the garment they may be left comparatively loose to augment freedom of movement. And said shoulder-straps 14 need not be disturbed in lowering the drop-seat *a*, since the releasing of said drop-seat and the lowering thereof is brought about simply by unhooking the ends of the belt-straps 16.

Changes in the specific form of my invention, as herein disclosed, may be made within the scope of what is claimed without departing from the spirit of my invention.

Having described my invention, what I claim as new and desire to protect by Letters Patent is:

1. A garment of the character described including a body portion having a drop-seat portion tapered upward and thus providing a free edge relatively short in length at the waist line of the garment, said body portion being extended at either side of the back to underlap said tapered drop-seat, suspenders for the garment, the rear end of each suspender being fastened to one of the extensions of said body portion, a pair of opposed loops affixed to the free corners of said drop-seat, a belt strap for each loop, one strap being secured at one end to the body portion of the garment at the junction of one suspender with said body portion, the other strap being similarly secured to the garment at the junction of the other suspender with said body portion, each strap being threaded through its respective loop, a fastener member on one

strap and a complementary fastening member on the other strap, said straps being adapted to be oppositely drawn about the waist of the garment and joined at their free ends through said fastener members, where by said drop-seat is releasably held snugly closed and the garment smoothly drawn about the waist of the wearer. 70

2. A garment of the character described, including a body portion having a drop-seat portion tapered upward and providing a free edge relatively short in length at the waist line of the garment, said body portion being extended at either side of the back to underlap said tapered drop-seat portion, suspender members for the garment, one member fastened to one of the extensions of the body portion and the other member fastened to the other of said extensions, opposed loop devices applied to one of said portions at the waist line of the garment, a pair of straps, each strap being secured at one end thereof to the other portion at the waist line, said straps being threaded through said loops and oppositely turned to hold the drop-seat closed, and means for releasably securing said straps against being loosened in said loops, said straps serving to hold the garment, at the waist thereof snugly and smoothly about the body of a wearer. 75

3. A garment of the character described, including a body portion having a drop seat portion, said body portion being formed with extensions underlying said drop seat portion at either side thereof, and suspenders for the garment attached to the front thereof and to said extensions, said suspenders comprising shoulder straps crossed at the back, the straps going over each shoulder connected with the extension on the opposite side of the body, and means for holding said drop seat in closed position. 100

4. A garment of the character described, including a body portion having a drop seat portion, said body portion being formed with extensions underlying said drop seat portion at either side thereof, and having tapered edges approaching one another at their upper ends, a pair of suspender straps for the garment attached to the front thereof and to said extensions, said suspender straps being crossed at the back and each extending in substantial alignment relative to the tapered edge of its respective extension whereby the rear of the garment is directly supported from the shoulders of the wearer through said extensions, and said extensions are caused to lie flat along the body of the wearer, and means for holding said drop seat in closed position. 105

In testimony whereof, I have signed my name to this specification.

ERICK O. FELLROTH.
